UNITED STATES PATENT OFFICE.

MATTHIAS BROCK, OF BOSTON, AND THOMAS H. SEELY, OF MALDEN, MASSACHUSETTS, ASSIGNORS, BY MESNE ASSIGNMENTS, TO UNITED SHOE MACHINERY CORPORATION, OF PATERSON, NEW JERSEY, A CORPORATION OF NEW JERSEY.

LASTING MACHINE.

Application filed August 22, 1917. Serial No. 187,594.

To all whom it may concern:

Be it known that we, MATTHIAS BROCK and THOMAS H. SEELY, citizens of the United States, residing at Boston, in the county of Suffolk and State of Massachusetts, and Malden, in the county of Middlesex and State of Massachusetts, respectively, have invented certain Improvements in Lasting Machines, of which the following description in connection with the accompanying drawings is a specification, like reference characters on the drawings indicating like parts in the several figures.

The invention to be hereinafter described relates to machines for manufacturing boots and shoes, and more particularly though not exclusively, to lasting machines, whereby the upper materials are worked over a last and innersole and secured in position. In its broad aspect the invention is not limited to use in connection with any particular type of lasting machine, but for the purpose of exploitation, it is herein described as associated with that type of lasting machine in which the upper materials are worked over the last by repeated operations on different portions and secured in lasted position by fastenings as the work progresses. A machine of this type is disclosed in United States Letters Patent No. 584,744, dated June 15, 1897.

In lasting shoes by the machine of the patent noted and other machines of this general type, the upper is worked over the last and edge of the innersole by means which successively pull different portions of the upper into lasted position where it is temporarily secured by tacks usually driven thru the marginal portions of the over-worked upper and into the innersole and last. During the inseaming operation these tacks, which in high grade shoes are driven comparatively close together, are liable to interfere with the awl or needle of the inseaming machine. To minimize this trouble, it has sometimes been the practice to permit the shoe to be held in lasted condition by the lasting tacks for a sufficient length of time for the upper to become set to a degree, and then to withdraw the lasting tacks and drive a less number of stay tacks. While this reduced the trouble it did not entirely overcome it and the additional operation of withdrawing the lasting

tacks and driving a less number of stay tacks increased the labor and cost of production.

It has been proposed entirely to dispense with tacks for temporarily holding the upper in lasted position on those shoes employing a sole having a lip, shoulder, or projection by driving separate staples thru overworked portions of the upper and lip, shoulder, or projection of the innersole above the plane of movement of the inseaming needle. The lip, shoulder, or projection, however, usually extends only part-way around the sole and is omitted about the heel seat in some makes of shoes, as for instance, those known as "welt shoes", and after securing the overworked upper to the lip, as suggested, it has been the custom to complete the lasting operation by another machine. These repeated operations detract from economic production, not only by reason of the increased labor necessary, but also the greater length of time required in completing the desired lasted condition of the shoe.

With a view to dispensing entirely with such separate operations and machines to complete the lasted condition of the shoe, a very important feature of the present invention consists in means for selectively driving separate fastenings into the work at different angles, the effect of which permits separate fastenings to be driven thru the upper and lip of the innersole and other fastening thru the upper and into the body of the innersole where the lip is omitted, so that the shoe including the sides and ends may be completely lasted in one operation.

While the invention in one of its broad aspects contemplates driving fastenings of any desired form or character at different angles in different parts of the work, it is preferred to drive separate fastenings of one character thru the overworked portions of the upper and lip of the innersole and another character of fastening thru the upper and into the body of the innersole. These fastenings are preferably driven into the work to remain permanently, those that secure the upper to the lip of the innersole being extended substantially in the general direction of and above the plane of the inseaming stitches transversely

of the lip, and consequently offering no practical obstruction to the awl and needle of the inseaming machine, while the separate fastenings that pass thru the upper and into the body of the innersole extend transversely of the plane of the shoe bottom.

When the shoe is to be completely lasted and the upper secured permanently in lasted position about the ends as well as along the 10 sides of the shoe, the separate fastenings employed to secure the upper to the lip of the innersole should be adapted to pass thru the toe stiffener or box-toe as well as the upper and lip. The other fastenings that 15 are driven thru the upper and into the body of the innersole in those parts of the inner-sole where the lip is omitted, should also pass thru the counter.

Another important feature of the present 20 invention, therefore, consists in means for selectively driving one character of separate fastenings thru portions of the upper materials and lip of the innersole and means for driving another character of fastening 25 thru other portions of the upper materials into the body of the innersole. In the illustrated embodiment of the invention, the machine is adapted to drive staples thru the upper materials and lip of the innersole 30 and to drive tacks thru other portions of the upper materials into the body of the inner-sole. To facilitate penetration by the fastening the toe stiffener or box-toe and the counter may be rendered more pliable and 35 more easily pierced by tempering these parts, as by heat and moisture.

While the invention contemplates completion of the lasted condition of the shoe in one operation, it may be desirable at 40 times or with certain shoe materials, that one or both ends of the shoe be lasted before or after the sides have been worked into and secured in lasted position. Under these conditions, the operation of end lasting is 45 liable to displace the end stiffener, such, for instance, as the counter. An important feature of the present invention, therefore, consists in means for driving separate fastenings through portions of the upper and 50 the lip of the innersole and other fastenings through other portions of the upper, the end stiffener, and into the body of the innersole, the effect being to hold the end stiffener 55 from displacement when the end of the shoe is subsequently lasted.

The lip of the innersole usually varies in its distance from the edge along different portions of the innersole, so that the driving position of the means for driving fastenings 60 through the upper and lip of the innersole suitable for one distance of the lip from the edge of the innersole will not be suitable for another distance. Therefore, another important feature of the invention consists 65 of means for varying the driving position of

the driving means in accordance with the position of the lip through which the fastenings are to be driven. This feature of the invention is carried into effect by a lip support, in the present instance of the invention, which engages the inside of the lip and is positioned by it for supporting the lip during the driving operation.

The best results in fastening the upper to the lip of the innersole are secured when 70 the upper is forced into the angle between the feather and lip and clamped against the lip during the driving of fastenings, but since the lip varies in its distance from the edge of the innersole in different portions 75 thereof, wiper movements that would properly locate the upper in the angle between the feather and lip at one part of the inner-sole, would not properly locate the upper at another part. The present invention, 80 therefore, contemplates as an important feature thereof, means for giving wiper movements to a wiper as determined by the position of the lip from the edge of the 85 innersole.

When fastenings are to be driven through the upper into the body of the innersole, as for instance, about the heel seat, the services of the lip support are no longer necessary, and increased wiper movements are 90 desirable to place the upper well over the heel seat and to cause fastenings to be driven thru the upper into the body of the innersole, farther from the edge of the last. Accordingly means is provided, as another 95 important feature of the invention, for removing the lip support from operative position and effecting increased or maximum wiper movements to lay the upper well over the shoe bottom and to position the fastenings 100 farther from the sole edge.

Selective driving of separate fastenings for securing overworked portions of the upper to the lip of the innersole and other fastenings through the upper into the body 105 of the innersole at a different angle, may be variously contrived, but as illustrated in the present form of the invention, the feeding of fasteners for one purpose is suspended during the feeding of fastenings for the 110 other purpose, and the change from one to the other is readily effected at the will of the attendant.

The present invention also provides a 115 novel construction of tack separator, and other features and important details and construction of parts which will be herein-after more particularly described, and these in addition to the features hereinbefore mentioned, will be definitely set forth by 120 the claims.

In the drawings:—

Figure 1 represents, in side elevation, a 125 lasting machine embodying the present invention;

Fig. 2 is a perspective view on an enlarged scale of the machine represented by Fig. 1, some of the parts being broken away to disclose the construction of other parts, 5 beyond;

Fig. 3 is a section detail showing one form of means for suspending the operation of the tack-driving means;

Fig. 4 is a detached detail showing the 10 connections for controlling the tack driving means and moving the lip support operating member;

Fig. 5 is an enlarged sectional view substantially on the broken line 5—5, Fig. 1, 15 some of the parts being omitted and others broken away for clearness of illustration;

Fig. 6 is a front elevation showing the tack separator and associated parts for delivering two tacks to be driven;

Fig. 7 is a perspective detached detail of 20 portions of the head and tack carrier slide and associated parts, portions being broken away;

Fig. 8 is an enlarged perspective detail 25 showing portions of the tack carrier slide and means for feeding wire to the staple forming mechanism;

Fig. 10 is a detail of the staple-forming and driving means, portions of the tack carrier being broken away;

Fig. 11 is a side elevation showing more 35 particularly the staple forming and driving slides;

Fig. 12 is a perspective view of a shoe 40 completely lasted by separate fastenings passed through the upper and lip of the innersole and other fastenings at a different angle passed through the upper and into the body of the innersole.

Fig. 13 is a perspective view of a shoe 45 having separate fastenings driven through overworked portions of the upper and lip of the innersole, and other fastenings driven through other portions of the innersole.

The machine comprises a column 2 supporting a head 3 that has bearings for the 50 main shaft 4 which may be rotated from any convenient source of power by suitable means, such for instance, as belt pulley 5. Mounted upon the main shaft 4 are the cams for effecting the desired movements of the 55 lasting instrumentalities, which, in the illustrated embodiment of the invention, comprise the gripper 6. The cams impart to the gripper 6 the closing movement to seize the upper, the updraw movement to pull the upper and stretch it about the last, and the overdraw movement to lay the pulled upper over the edge of the innersole. If desired, the machine may also be provided with a usual form of mechanism for imparting to 60 the gripper plaiting movements. These

features, together with their connections for imparting the desired movements to the gripper may be of usual construction and operation and substantially as disclosed by United States Letters Patent, No. 584,744, 70 hereinbefore mentioned. In this type of lasting machine, the upper is worked into lasted position by repeated operations of the gripper on different portions of the upper, and while the present invention is well 75 adapted for use in connection with this type of machine, it may also be advantageously employed in connection with other forms of lasting machines, and in the broadest sense, certain features of the invention 80 may be employed in other relations.

The term "lipped innersole" is herein employed in its broad sense, and includes not only innersoles having a portion of the stock thereof turned upwardly to constitute a lip, 85 but all forms of innersoles provided with a projection or shoulder extending from the surface plane of the innersole; and the term "fastening" is also herein employed in its generic sense.

In order that a last having a lipped innersole and an assembled upper, to be herein termed the shoe, may be readily positioned for the operation of the machine, shoe positioning means of any desired character 90 may be employed. In the present instance of the invention, the shoe positioning means comprises a sole rest 7, against which the bottom of the shoe *a* is placed and held by the attendant, and an edge gage 8, adapted to bear upon the edge portion of the shoe 95 as it is moved to present different parts for treatment. The sole rest 7 is supported by a bracket 9 projecting from the head frame of the machine.

The head frame 3 of the machine has secured thereto a bracket 10, Figs. 1 and 2, provided with an elongated bearing 11 for a counter shaft 12. A sprocket wheel 13 is secured to the counter shaft 12 and is driven 110 by a sprocket chain 14 operated by a sprocket wheel 15 secured to the main shaft 4, the construction being such that as the main shaft 4 is rotated the counter shaft 12 will be continuously driven in desired 115 timed relation with the main shaft. The counter shaft 12 carries a series of cams and these are utilized to operate certain parts associated with the means for securing the upper to the lip of the innersole. The 120 fastenings which secure the upper to the lip of the innersole are formed as staples and are made and inserted by the machine, while the fastenings which secure the upper to the body of the innersole at an angle to the 125 fastenings that pass thru the lip of the innersole are tacks and are furnished from a suitable supply.

The head frame 3 has mounted thereon for reciprocating movements, the main slide 130

16, the front portion of which slide is devised for carrying or forming and carrying, as the case may be, the fastenings to fastening-inserting position and wiping the upper over the edge of the innersole. The main slide 16 is actuated by a slide actuating cam 18 mounted on the main driving shaft 4 and having a camway or path 19, suitable connections being formed, as will 10 hereinafter more fully appear, to transmit motion from the slide actuating cam 18 to the main slide 16.

As hereinbefore stated, the fastenings which are to secure the upper to the lip of the innersole, are formed and driven by the machine and such fastenings, when driven, extend thru the upper and transversely thru the lip of the innersole, or in substantial parallelism with the bottom of the shoe.

20 The main slide 16 is provided with longitudinally extending guideways for the staple-forming and driving means as illustrated in Fig. 11, and the angular relation of such guideways to the plane of the shoe 25 bottom is such that when the shoe is positioned for operation of the machine by the shoe positioning means, the staples will be driven transversely thru the upper and the lip of the innersole in a direction substantially parallel to the bottom of the shoe. The staple-forming and driving means consist of a former slide 20, Fig. 10, provided 30 with wire bending portions 21 which are adapted to bend portions of a wire about an anvil to form the legs of the staple. In 35 the present instance of the invention, the former slide 20 carries a cutter 22 adapted to cut a piece of the wire b, Fig. 10, as the former slide 20 is moved forwardly. This 40 cutter may be of any preferred character, but is shown as comprising a steel block secured to the former slide 20 and movable therewith across the face of a bushing 23 thru which the wire b is fed as will presently appear. Extending forwardly from 45 the projecting portions 21 of the former slide is a staple-forming table 24 on which the wire b rests during the staple-forming operation, and by which the formed staple 50 is moved forwardly towards driving position as the staple former 20 is reciprocated in its guideway 25, Fig. 10.

The staple former slide 20 may be variously actuated to perform its staple-forming function, but in the present instance of the invention, the staple-forming slide is provided with rack teeth 26, Fig. 11, which are in operative engagement with the segment teeth 27 (Fig. 5) formed on an arm 28 pivotally mounted at 29 and actuated by an arm 30, the end portion of which is provided with a pin or roll 31 adapted to travel in the path 32 of a cam 33 mounted on the counter shaft 12, the construction being such 65 that as the counter shaft 12 is rotated, the

former slide will be reciprocated in the main slide to form the staple.

The anvil 34 about which the wire is bent to form the staple, is mounted for rocking movement upon a stud 35, Fig. 9, and passes 70 thru a slot or opening 36 formed in the front portion of the main slide as indicated in Figs. 7 and 8.

The anvil 34 is preferably formed as a bent finger as indicated in Fig. 9, secured by 75 suitable means such as the screws 37 to a carrying arm 38, the hub portion of which is mounted upon the stud 35. Projecting backwardly from the hub portion of the arm 38 is a shoulder 39 adapted to engage 80 a stop 40, Fig. 9, projecting from the anvil actuator 41 conveniently mounted on the stud 35. In order that the anvil may yield in case of any obstruction as it is moved toward staple-forming position, there is a 85 yielding connection between the anvil and its actuating arm 41. This is accomplished by means of a spring 42 interposed between the lugs 43 and 44 projecting from the arms 38 and 41 respectively. The anvil actuator 41 is provided with an elongated slot 45, one end of which slot is downturned as at 46. A roller carrying stud 47 projecting from the fixed head frame 3 engages the slot 45, the construction being such that as 90 the main slide 16 is reciprocated, the roller carrying stud 47 causes the anvil 34 to move to and from staple-forming position.

The front or leading end portion of the main slide 16 is provided with a passageway or opening 48 thru which the formed staple is forced by the driver into the work. In the present instance of the invention, the driver consists of the driver slide bar 49, Fig. 11, provided with a series of teeth 50 which are in operative engagement with the teeth of a segment 51, Fig. 5. The segment 51 is mounted on an arm 52 which is pivoted to a bracket 53 extending from the main slide 16. Pivotal support of the segment carrying the arm 52 is afforded by a pin 54, Fig. 2, extending downwardly from the bracket 53. The hub of the segment arm 52 which is mounted upon the pin 54 has an arm 55 to which is pivotally connected 110 at 56 a link 57 which is itself pivotally connected at 58 to an arm 59 pivotally supported on a fixed pin 60 projecting upwardly from a bracket 61 secured to the machine head. The hub 62 of the arm 59 is provided with an actuating arm 63, the end of which is provided with a pin or roll 64 which engages a cam groove 65 of the cam block 33, the construction being such that upon rotation of the counter shaft 12 and perforce the 115 cam block 33, the segment arm 52 will be appropriately actuated to drive the staple previously formed by the staple-forming mechanism.

When the staple has been formed about 120

the anvil 34 by forward movement of the staple-forming slide 20, the anvil is lifted from its staple-forming position. This action of the anvil is effected in the present instance of the invention by forward movement of the main slide 16 by which the anvil is carried, the fixed pin 47 at such time riding in the elongated slot 45 of the actuator 41. As the anvil is lifted by the forward movement of the main slide 16, the staple-forming and driving slides are also moved forwardly an appropriate amount to carry the staple which at this time rests upon the table 24, forwardly into driving position.

The wire for forming the staples is fed to the staple-forming mechanism by suitable feeding means which consists of feed rolls between which the wire passes from a suitable source of supply. As indicated in Fig. 8, the feed rolls 66 and 67 are mounted upon the main slide 16 and move with it. To this end the slide 16 is provided with a projecting portion 68, Fig. 8, in which is mounted the shaft carrying the upper feed roll 66. The feed roll 66 has at one side thereof the toothed wheel or pinion 69 which is operatively engaged with a similar toothed wheel or pinion 70 connected to the lower feed roll 67, the construction being such that the upper and lower wire feed rolls are caused to rotate in unison. In order that different sizes or gauges of wire may be fed to the staple-forming mechanism, one of the feed rolls is yieldingly mounted for movement toward and from the other feed roll. The lower feed roll 67 is mounted on an arm 71, Fig. 8, pivotally connected at 72 to the main slide and having a side projecting arm 73 between which and an abutment 74 is interposed a spring 75 normally acting to force the lower feed roll 67 yieldingly toward the upper feed roll 66 but yet permitting separating movement of the lower feed roll from the upper feed roll.

Intermittent rotative movement is imparted to the feed rolls to feed the wire at intervals by suitable actuating means. The upper feed roll 66 is provided with an appropriate wheel 76, Fig. 8, having elongated teeth 77 adapted to be engaged by an actuating pawl 78. On the actuating pawl 78 is a pivot pin 800 mounted to rock in a sleeve 79 carried by an arm 80 projecting from a rocking sleeve 81 which is supported by a stud 82 (Fig. 2). On the pin 800 of the pawl 78 is a torsion spring 801 one end of which is connected to a collar 802 fixed to the pin 800 and the other end of which rests under tension on a pin 803 on the arm 80, the pawl 78 being normally held by the spring 801 in engagement with the teeth of the wheel 76. The rocking sleeve 81 has projecting from the end thereof remote from

the arm 80 another arm 83 (Fig. 2) provided with a pin or roller 84 which engages the face groove 85 formed in the face of the cam block 33, the construction being such that as the counter shaft 12 is rotated, the pin or roller 84 will move in the cam slot 85 and cause appropriate rocking movement to the sleeve 81 and step-by-step turning movement to the wire feed rolls. When the main slide is reciprocated, as will herein-after more fully appear, the end of the actuating pawl 78 will ride in the elongated teeth 77 of the ratchet secured to the upper feed roll without being disengaged from operative relation therewith.

As indicated in Fig. 2, a wire guide 86 provided with a guide opening may be provided to direct the wire from a source of supply to the nip between the upper and lower feed rolls, whence it will pass into the bushing 23 as indicated in Fig. 10 and as previously described.

The lip of the innersole varies in its distance from the edge around different portions of the shoe, and in some forms of innersoles, the lip extends only partway about the innersole. In order that the upper when worked into lasted position may be forced into the angle between the feather and the lip of the innersole, it is consequently desirable that the wiper which forms an element of the present machine shall have movements corresponding to the distance of the lip from the edge of the innersole. Likewise, about those portions of the shoe where the lip is omitted, it is desirable that the wiping action of the wiper be increased in order to lay the upper well over the innersole for receiving fastenings which are to be driven thru the overworked portions of the upper into the body of the innersole at a greater distance from the edge of the sole than the rib. Since the staples are to be driven thru the overworked portions of the upper and the lip of the innersole, and the position of the lip from the edge of the innersole varies, it is desirable to adjust or vary the driving position of the driving means for the staples to accord with the distance of the lip from the edge of the innersole. The present invention, therefore, contemplates means controlled by the position of the lip of the innersole for determining the extent of wiper movements and also the driving position of the driving means.

The means for determining the driving position of the driving means for the staples and the extent of wiper action while driving the staples is comprised by a member 125 adapted to engage the inner side of the lip of the innersole and support it while the staples are being driven. That the lip may be firmly held during the staple-driving operation, the present invention also con-

templates that the lip shall be clamped between the said member and an opposing member at each staple-driving action.

- Pivots mounted at 87 on the bracket 88 projecting from the machine head, is the rocker arm 89 carrying a pin 90 on which is pivotally mounted the lip supporter 91, a spring 92 normally acting to hold the lip supporter downwardly against the surface 10 of the innersole of a shoe positioned in the machine. The lip supporter 91 is further sustained for sliding movement by the lower portion of a bracket 900 adjustably secured to the machine head as indicated in Fig. 1. The upper arm 93 of the rocker 89 is operatively connected to a measuring rod 94. The measuring rod 94 is provided with collars 95 between which extends a pin projecting from the upper arm 93 of the rocker. The measuring rod 94 is properly sustained in operative position by a bearing 96 projecting from the bracket 97 secured to the machine head and extends rearwardly and is connected at its rearward end at 98, Fig. 5, to a projection on a block 99. The block 99 is pivotally mounted on a fixed support which comprises a bracket 100 secured to the machine head 3 by suitable means such as the bolt 101. The block 99 while free for turning movement about its pivotal mounting, has a pin 102 extending into a slotted link 103 carried by a fixed stud 104 which rises from the bracket 53 projecting from the main slide 16.
- It will be seen that when the slide 16 and bracket 53 are moved rearwardly the slotted link 103 acting on the pin 102 will turn the block 99 clockwise, causing rearward movement of the measuring rod 94 and consequent movement of the lip supporter 91 inwardly of the shoe and away from the lip.

Extending rearwardly from the pivotal point of the block 99 is an arm 105 which is normally under the influence of means 45 tending yieldingly to turn the block 99 counter-clockwise. Said means consists of a spring 106 which surrounds a rod 107. One end of the rod 107 bears against the arm 105 of the block 99 while the other end 50 thereof extends loosely into an adjusting sleeve 108 carried by the bearing 11, the construction being such that by suitable manipulation of the threaded sleeve 108 the tension of the spring 106 may be suitably 55 varied.

When the slide 16 moves forward the slot in the link 103 frees the pin 102 and allows the block 99 to be turned under the influence of the spring 106 an amount 60 determined by the measuring rod 94 and lip supporter 91, movement of which and of the block 99 ceases when the lip supporter comes into engagement with the lip.

Loosely mounted upon the stud 104 ex- 65 tending upwardly from the member 53

which is movable with the main slide 16 is the slide operating arm 109 having a pin or roll 110 at its free end for engagement with the cam path 19 of the slide actuating cam 18. Formed integral with the hub of the slide actuating arm 109 is the controlling arm 111 provided with a pin 112 extended downwardly therethru and engaging an elongated slot 113 formed in the block 99, the construction being such that the amount of movement imparted to the main slide 16 and the parts carried thereby thru the actuating arm 109 will depend upon the position of the slot 113. For instance, if the block 99 be in position to place the slot 113 parallel to the slide 16, the movement imparted to the slide 16 by the actuating arm will be determined solely by the cam path 19; but if the slot 113 should be positioned more or less diagonally with respect to the movement of the main slide, then the amount of movement imparted to the main slide will vary according to the diagonal position of the slot. That is, when the slot 113 is in a position inclined to the direction of movement of the slide 16 the arms 109, 111 act as a lever of the third class fulcrumed on the cam roll 110, the lateral movement of the pin 112, as the slide is advanced by its cam, acting on the pivot 104 to impart a movement to the slide in addition to the movement which would be effected by the cam path 19 alone. Of course, when the slot 113 is parallel to the direction of movement of the slide 16, the movement of the slide is at its minimum, determined solely by the path 19. Also, when the block is held in the position shown in Fig. 5 and is not allowed to be turned by the spring 106, the movement of the slide is at its maximum. Means for thus holding the block 99 against movement to produce maximum movement of the slide will be hereinafter described. When the parts are at rest with the slide in its rearward position as indicated in Fig. 5, the slotted link 103 by its engagement with the pin 102 will hold the block 99 from movement responsive to the spring 106, but when the machine is started and the main slide 110 starts its movement toward the front of the machine, the slotted link 103 will no longer prevent turning movement of the block 99 responsive to the spring 106 and the amount of such turning movement and 115 enforce the position assumed by the slot 113 will depend upon the amount of movement permitted the lip support 91, the construction being such that when the lip support meets the inside of the lip of the innersole, the block 99 will be positioned by reference to the lip and the slot 113 of the block 99 will be correspondingly positioned. 120

Thus, when the lip support 91 meets the inside of the lip, the amount of movement 125

to be imparted to the main slide to clamp the lip between the supporter and a front part or face 114 of the slide and to position the driving part of the driving means 5 will be determined.

The wiper in the present instance of the invention, is formed by the lower front end surface 115 of the main slide 16, the construction being such that when the lip supporter 91 has determined the amount of movement to be imparted the main slide by reference to the position of the lip from the edge of the innersole, the amount of wiping movement to be imparted to the wiper, as 15 well as the driving position of the driving means is determined.

After the lip supporter 91 has thus performed its positioning function, and the position of the block 99 is determined by 20 the lip supporter, it should be locked in the lip-determined position. To this end the block 99 has a segmental portion 116, Fig. 5, provided with a series of teeth 117 which are adapted to be engaged by a corresponding series of teeth 118 carried by an arm 119 whose hub portion 120 is mounted for turning movement upon the stationary pin 29. Extended from the hub portion 120 is an arm 121 to the end of which is 25 connected one end of a spring 122, the other end of the spring being fixed to a pin 123, the construction being such that the spring 122 normally acts to throw the teeth 118 into locking engagement with the teeth 117. Extending downwardly from the arm 121 is a pin 124 carrying a roll riding along the face cam 125 formed on the cam block 33, so that when the lip supporter has determined the position of parts 30 as above described, the face cam 125 will permit the parts to be locked in their determined position by the spring 122.

One of the important features of the present invention consists, as hereinbefore 45 stated, of means for selectively driving separate fastenings thru overworked portions of the upper and lip of the innersole and for driving other fastenings thru other portions of the upper into the body of the innersole; and it is appropriate at this time, therefore, to describe the means employed 50 for driving fastenings thru the upper into the body of the innersole and a means for selectively determining which of such fastenings shall be driven.

In the present instance of the invention, the fastenings which are to be driven thru overworked portions of the upper into the body of the innersole, consist of tacks, and as 55 a preferred form of this feature of the invention, means are provided for driving a plurality of such tacks.

Mounted in convenient position on the head of the machine frame are the two raceways 126 and 127 which may be of usual

character for feeding tacks toward a suitable tack separator. Extending across the open end portions of the raceways 126 and 127 is the separator block 128, Fig. 6, having the downwardly-extending openings 129 for 70 the passage of separated tacks toward the tack carrier or front portion of the main slide. The downwardly-extending passages 129 have open side portions in alignment with the end portions of the raceways 126 and 127, and such passageways 129 preferably diverge downwardly as indicated in Fig. 6 so that as the tacks delivered to the passageways pass downwardly to the tack carrier, they will be separated as determined 75 by the divergent character of the guides. Mounted for reciprocating movement in the separator block 128 is the tack separator slide 130 having a single tack separating passage 131 and an opening 132 80 for the reception and passage of two tacks, the construction being such that as the separator slide 130 is reciprocated past the end portions of the raceways 126, 127, the single separating slot 131 will detach the 85 endmost tack from each raceway and cam or move it outwardly, as the slide moves to the left, Fig. 6, so that the tacks thus separated will drop into the passageways 129 and pass into the tack carrier when 90 that element is in tack-receiving position. The means for operating the separator slide 130 may be variously contrived, and is preferably yieldingly actuated in both directions to the end that should a tack be 95 caught so as to obstruct movement of the slide, no parts of the machine will be broken or injured. To this end, the tack carrier slide 130 (Fig. 5) is provided with a series of rack teeth 133 which are engaged 100 by the teeth of a segment 134 mounted on one arm of a lever 135 pivoted at 136 and connected at 137 to the lever actuating means. Mounted for reciprocating movement with the main slide 16 is the block 105 138 (Fig. 7) having a slot 139 thru which passes the supporting pin 140 extending from the fixed head frame 3. Thru the other end portion of the block 38 extends the stud or pin 35 which connects the block 110 115 for movement with the main slide 16. The block 138 is provided with a slot 141 extending thru the top thereof and below the slot said block carries a spring 142, one end of which rests against the pin 35 120 and the other end of which rests against the lower end portion of the swivel bearing 143. Thru the upper portion of the swivel bearing 143 extends the slide actuating rod 144. A spring 145 surrounds the 125 actuating rod 144, one end portion of which bears against the upper portion of the swivel block 143 and the other end portion of which bears against the end of the lever arm 135 (Fig. 5), the construction being 130

such that should the tack separator be obstructed in its movement in either direction, one or the other of the springs 142 and 145 would yield to thereby prevent the breaking of parts.

- The front end portion of the main slide 16 is provided with the tack carrying openings 146, one of said openings 146 being at each side of the staple-driving passage 10 48, as indicated in Figs. 7 and 10. Between the upper and lower terminal portions of the tack carrier openings 146, the front portion of the main slide 16 is preferably slotted or recessed as at 147 to receive tack- 15 sustaining springs. In the present instance of the invention, these tack sustaining springs consist of two members 148 and 149 having formed in the ends of each a separable tack-sustaining portion 150. 20 These spring tack holders may be appropriately held in operative position by suitable securing means, as for instance, the screws 151. It will thus be apparent that the present invention provides a main slide 25 having a driving passage for one form of fastening to be driven thru the upper and the lip of the innersole, and a plurality of fastening passages, one at each side of the other fastening passage and arranged 30 at an angle thereto for the insertion of a plural number of fastenings simultaneously thru the upper and into the body of the innersole at an angle to the other fastenings. 35 The tack handling mechanism above described is not claimed herein, per se, since it forms the subject-matter of a divisional application Serial No. 9324 filed February 10, 1925.
- A broad aspect of the present invention 40 contemplates means under the control of the attendant for rendering one fastening-driving means operative and the other inoperative at will. This characteristic of the invention consists in suspending the feed of 45 one fastening while the other fastening is being driven. When fastenings are being driven thru overworked portions of the upper into the body of the innersole, as distinguished from the lip of the innersole, it is 50 expedient to remove the lip supporter from any interference with the increased wiper movements which are desirable. Therefore, in the broad aspect the invention contemplates that when the attendant manipulates 55 the means for selectively determining which character of fastenings shall be driven, and throws into operative condition the means for driving fastenings thru the upper into the body of the innersole, he will at the 60 same time, without further attention on his part, remove the lip supporter from operative position or move it an increased distance away from the edge of the innersole and at the same time cause maximum wiper movements to be imparted to the wiper. 65

Mounted in suitable guideways 152 on the machine head is the driver bar 153, Fig. 2, carrying the drivers 154, each of which is adapted to drive a tack thru the tack carrier into the body of the innersole. The 70 driver bar 153 may be actuated as usual in this class of machines, and as indicated by the patent hereinbefore referred-to. In the present instance of the invention, the driver bar has secured thereto at the upper portion a collar 155, Fig. 2, which may be held in position by suitable nuts 156. Below this collar is a yielding buffer 157 which is adapted to take up shock incident to the driving impact. Pivottally mounted on the machine head as at 158, Fig. 3, are the sustaining members 159 connected by suitable rack teeth 160 for movement in unison about their pivots 158. When the sustaining members 159 are in closed position as indicated in Fig. 2, and by full lines in Fig. 3, they are adapted to sustain the driver bar in its up position as determined by the usual lifting cam; but when the sustaining members 159 are moved into their dotted line position, Fig. 3, they permit the driver bar to be actuated for driving tacks. One of the members 159 is provided with a projecting arm 161, Figs. 2 and 3, to which is pivotally secured a rod 162, the other end of said rod being pivotally connected to an arm 163 secured to the rocker rod 164 sustained in suitable bearings by the machine head. Clamped to the lower end portion of the rocker rod 164 is the block 165 having a 100 stop finger 166 which, when the rocker rod 164 is turned into position to insert the sustaining members 159 under the collar of the driver rod and perforce hold the driver in inoperative position, has its end projected into the path of movement of the tack separator slide 130 with the result that the tack separator slide is rendered inoperative for feeding tacks; but when the rocker rod 164 is turned in the opposite direction to withdraw the sustaining members 159 into dotted line position, Fig. 3, the end of the stop finger 166 is removed from the path of the tack separator and the latter and the drivers, become operative to feed and drive tacks. 110 115

Loosely mounted in axial alinement with the counter shaft 12, is a sleeve 167 having a series of teeth 168 which are operatively engaged with teeth 169 formed on a segment 170 extending from a member 171 loosely mounted on the stud or shaft 82 and partly surrounding the sleeve 81 (Fig. 5). Extending from the member 171 is a projection 172 pivotally connected to an arm 173 from which rises a pin 174. From the pin 174 extends the link 175 which is connected for movement with the block 165 by means of a pin 176, Fig. 4, the construction being such that as the member 167 is operated by the handle 177, Fig. 2, the rocker 120 125 130

rod 164 will be turned in appropriate direction to render the tack feeding and driving means operative or inoperative according to the direction of movement of the 5 rocker rod. In the position of parts indicated by Fig. 2, the tack driving means is shown as inoperative position and the staple driving means in operative position. By movement of the handle 177 downwardly, Fig. 2, the parts will be operated to move the rocker rod 164 counterclockwise, Fig. 2, to render the drivers operative and to withdraw the finger 166 from the path of the tack separator. In order to render 10 the staple driving means inoperative, when the handle 177 is turned downwardly as described, the member 171 connected to the segment 170 has secured thereto a pawl trip arm 178, Fig. 2, a roll 179 on the end of 20 said trip arm being adapted to engage the end 180 of the pawl 78 and move said pawl against the spring 801 from operative relation with the ratchet 76 of the wire feeding mechanism.

25 In order to remove the lip supporter out of the way of the wiper and tack driving elements while driving tacks through the upper into the body of the innersole, the present invention contemplates that upon 30 manipulation of the hand lever 177 to inaugurate the action or operation of the tack driving means, that the measuring rod 94 shall be moved rearwardly thereby to remove the lip supporter farther away from 35 the edge of the innersole. To this end the link or yoke 175 has an upwardly projecting member 181 as indicated in Fig. 4, connected at 182 to the pin 176 and having a socketed portion 183 adapted to engage a 40 pin or roll 184 secured to the measuring rod 94, substantially as indicated in Fig. 2. The pin or roll 184 may be secured to the measuring rod 94 by any approved form of connection, and as illustrated, the measuring 45 rod 94 has a sleeve 185 thereon adapted to be clamped in adjusted position by suitable means such as the bolts 186.

Movement of the measuring rod 94 rearwardly by the mechanism described causes 50 the block 99 to be turned clockwise (Fig. 5), and the slot 113 in the block 99 to be placed at its greatest inclination to the direction of movement of the slide 16 which carries the wiper 115. Hence upon rotation 55 of the cam 18 the slide 16 has imparted to it not only the movement due to the contour of the cam path 19, which alone imparts a minimum movement to the slide, but also the movement produced by inward 60 movement of the pin 112 engaging the inclined slot 113 and mounted on the arm 111. The arm 111 and the arm 109 constitute a lever fulcruming on the cam roll 110 and causing the pivot 104 on the slide to move 65 forwardly and impart additional move-

ment to the slide so that with the slot in its extreme angular position maximum movement is imparted to the slide, as is desirable when the drivers 154 are in use and those parts of the shoe where the innersole rib is omitted are being wiped over and secured, as shown for instance at *d* and *g* in Figs. 12 and 13 respectively.

When the shoe is to be completely lasted in accordance with one aspect of the present invention, the upper will be worked over the last and edge of the innersole and separate fastenings will be driven thru overworked portions of the upper and lip of the innersole along the lipped portion 75 thereof, and at those portions of the innersole where the lip is omitted, fastenings will be driven thru other portions of the upper into the body of the innersole, so that the shoe is made ready for the operation of inseaming or other treatment. The invention also lends itself for advantageously treating those shoes where the end portions are molded to conform to the end of the last. In such case, the molded end portions may be secured permanently as before in lasted position, or, if desired, the attendant may modify the action of the machine about the ends of the shoe or suspend the driving of fastenings at these points, or he 80 may drive a sufficient number of fastenings to assist in maintaining the molded end portions of the shoe in lasted position. In cases where the shoe is to be completely lasted by driving permanent and separate 85 fastenings thru the overworked upper into holding relation with the innersole, the attendant will ordinarily continue the driving of fastenings along one side about the toe and along the other side and at these 90 places the fastenings will be driven thru the overworked upper and transversely of the lip; but when a portion of the shoe is reached where the lip of the innersole is omitted, as for instance, about the heel seat, 95 he will throw the previously active driving means out of operation and inaugurate the insertion of fastenings, thru the upper and into the body of the innersole. This condition of the shoe when thus completely 100 lasted in accordance with the present invention, is graphically illustrated by Fig. 12. Here it will be noted that the fastenings *c* driven thru overworked portions of the upper and lip of the innersole are 105 driven in a direction substantially parallel with the surface plane of the shoe bottom, whereas, the fastenings *d* which pass thru the upper into the body of the innersole are nearly at right angles to the same 110 plane.

In those cases where the shoe is not to be completely lasted in the one machine, but is to be subsequently end lasted, it is expedient to retain or anchor the end stiffener in 115

place that it may not be disturbed as the end lasting devices operate. This applies both to the toe and heel ends, but more particularly to the heel because the counter is 5 retained in position usually by a single tack. Sometimes this single tack is driven, as indicated at *e*, Fig. 13, and gives little assurance that the counter *f* will not be disturbed in its assembled relation with the 10 upper and innersole as the end lasting devices, such for instance, as the heel band, act upon the shoe. Under these conditions, the present invention contemplates that in addition to driving separate fastenings 15 thru overworked portions of the upper and lip of the innersole along the sides, that the operative may, at his will, secure the upper and the forward portions of the counter at each side of the heel approximately at the 20 line of the heel breast. This he is enabled to do by suspending the insertion of the staples thru the overworked portions of the upper lip, and setting in operation the tack driving means, so that by presenting 25 the shoe in proper position, tacks *g* may be driven thru the upper, counter, and innersole and definitely secure these parts, including the counter, from displacement during subsequent treatment of the shoe. 30 Usually it will be desirable to stop the machine when passing from staple to tack-driving and vice versa, although, so far as the selective control of the machine operation is concerned, this is not necessary. To 35 stop the machine any usual form of stopping means may be employed which may act to arrest the machine parts in a predetermined position. In the present instance a treadle rod 187 of usual construction and 40 operation, may control a suitable brake 188 to effect machine stoppage at a predetermined point, but since the particular form of brake or stop mechanism is not of the present invention, it needs no further description herein. 45

A form of stop mechanism well adapted for use in this machine is disclosed in United States Letters Patent No. 1,356,406 granted October 19, 1920 on application of 50 T. H. Seely.

What is claimed is:—

1. A machine of the character described having, in combination, means for working an upper over a sole upon a last, and means 55 for inserting separate fastenings at different angles to the plane of the bottom of the sole during relative feeding movement of the shoe and fastening inserting means in relatively fixed planes to secure the upper in overworked position.
2. A machine of the character described having, in combination, work positioning means for positioning the work for successive operations in substantially the same 60 plane, means for inserting separate fasten-

ings into the work in different directions relative to the surface of the work, and means for selectively determining at the will of the attendant which of the separate fastenings shall be inserted. 70

3. In a machine of the character described, the combination of means for inserting separate fastenings into the overworked margin of an upper, means for inserting other separate fastenings into the 75 overworked margin of an upper at a different angle, and means for selectively rendering one of said inserting means operative and the other functionally inoperative.

4. In a machine of the character described, the combination of work positioning means, means for working the margin of an upper over a last, means for inserting separate fastenings into the overworked margin in predetermined angular relation thereto, means for inserting other separate fastenings into the overworked margin at a different angle thereto, and means under control of the attendant for rendering one of said means operative and the other functionally inoperative at will. 80

5. In a machine of the character described, the combination of work positioning means, means for driving separate fastenings into an overworked upper and innersole, and means for driving other separate fastenings into an overworked upper and innersole at substantially right angles to the direction of the first-mentioned fastenings, and means for selectively rendering one of said driving means operative and the other functionally inoperative. 95

6. A machine of the character described, having, in combination, work positioning means, means for driving separate fastenings into the work at one angle thereto and other separate fastenings at a different angle thereto, and manually controlled means for rendering the machine alternatively operative for driving one set of separate fastenings and then the other. 105

7. A machine of the character described, having, in combination, means for positioning a shoe, means for driving separate fastenings into the innersole of the shoe, means for driving other separate fastenings into the innersole of the shoe at a different angle, and means for selectively rendering one driving means operative and the other functionally inoperative. 115

8. A machine of the character described, comprising, in combination, means for positioning a last having an innersole and assembled upper, means for driving separate fastenings thru the upper into the material of the innersole, means for driving other separate fastenings thru the upper and into the material of the innersole at a different angle. 125

9. A machine of the character described, 130

comprising, in combination, means for positioning a last having an innersole and assembled upper, means for driving separate fastenings thru the upper into the material of the innersole, means for driving other separate fastenings thru the upper and into the material of the innersole at a different angle, and means for selectively rendering one of said driving means effective and the other ineffective.

10 10. In a machine of the class described, the combination of means for positioning a last having a lipped innersole and an assembled upper, means for inserting separate fastenings thru the upper and lip of the innersole, and means for inserting other separate fastenings thru the upper and into the body of the innersole.

11 11. In a machine of the class described, the combination of means for positioning a last having a lipped innersole and an assembled upper, means for driving separate fastenings thru the upper and lip of the innersole, means for driving other separate fastenings thru the upper and into the body of the innersole, and means for selectively rendering one of said driving means effective and the other ineffective.

12 12. A machine of the class described having, in combination, means for positioning a last having a lipped innersole and an assembled upper, means for driving separate fastenings thru portions of the upper transversely of the lip of the innersole, and means for driving other separate fastenings at a different angle thru other portions of the upper into the body of the innersole.

13 13. A machine of the class described having, in combination, means for positioning a last having a lipped innersole and an assembled upper, means for driving separate fastenings thru portions of the upper transversely of the lip of the innersole, means for driving other separate fastenings at a different angle thru other portions of the upper into the body of the innersole, and means operable at will for rendering one of said driving means operative and the other inoperative.

14 14. A machine of the class described, having, in combination, means for working an upper over a last having a lipped innersole, means for driving separate fastenings thru the upper and lip of the innersole, and means for driving other separate fastenings thru the upper into the body of the innersole at a different angle.

15 15. A machine of the class described, having, in combination, means for working an upper over a last having a lipped innersole, means for driving separate fastenings thru the upper and lip of the innersole, means for driving other separate fastenings thru the upper into the body of the innersole at a different angle, and means for rendering

one of said driving means functionally inoperative while the other is operative.

16 16. A machine of the class described, having, in combination, a gripper and actuating mechanism therefor constructed and arranged to pull successive portions of an upper about a last and over the edge of an innersole provided with a lip or projection, means for driving separate fastenings thru each overworked portion of the upper and innersole lip or projection, and means for driving other fastenings thru the overworked upper and into the body of the innersole about that portion of the innersole devoid of the lip or projection.

17 17. A machine of the class described, having, in combination, a gripper and actuating mechanism therefor constructed and arranged to pull successive portions of an upper about a last and over the edge of an innersole having a lip or projection, means for driving separate fastenings thru the overworked portions of the upper and the innersole lip or projection, and means for driving other fastenings thru the upper and into the body of the innersole.

18 18. A machine of the class described, having, in combination, a gripper and actuating mechanism therefor constructed and arranged to pull successive portions of an upper about a last and over the edge of an innersole having a lip or projection, means for driving separate fastenings through the overworked upper and through the lip or projections of the innersole, and means for driving other separate fastenings thru the upper and into the innersole at an angle to the fastenings passing thru the innersole lip or projection.

19 19. A machine of the class described, having, in combination, means for working an upper about a last and over the edges of an innersole having a lip or projection, means for driving separate fastenings thru overworked portions of the upper and transversely thru the lip or projection at a predetermined angle relative to the bottom of the shoe, and means for driving other fastenings thru the upper and into the innersole at a different predetermined angle to the bottom of the shoe.

20 20. A machine of the class described, having, in combination, means for working an upper about a last and over the edge of an innersole having a lip or projection extending thruout a part of the innersole, means for driving permanent fastenings thru overworked portions of the upper and the innersole lip or projection, and means for driving other permanent fastenings thru the upper and into the innersole where the innersole lip or projection is omitted to complete the preparation of the shoe for inseaming.

21 21. A machine of the class described, having, in combination, means for working an

- upper about a last and over the edge of an innersole provided with a lip, means to force the upper into the angle formed by the feather edge and lip of the innersole, means 5 to drive separate fastenings thru successive overworked portions of the upper and the lip of the innersole, and means for driving other separate fastenings thru the upper and into the body of the innersole.
- 10 22. A machine of the class described, having, in combination, means for working an upper about a last and laying the upper upon an innersole provided with a lip, means for driving separate staples thru overworked 15 portions of the upper and the lip of the innersole, and means for driving tacks thru other portions of the upper into the inner-sole.
23. A machine of the class described, having, in combination, means for working an upper about a last and over the edge of an innersole provided with a lip, means for driving separate staples thru the overworked portions of the upper and transversely thru 25 the lip of the innersole, and means for driving tacks thru other portions of the upper and into the innersole at an angle to the staples.
24. A machine of the class described having, in combination, means for working an upper about a last and over the edge of an innersole provided with a lip, means to force the upper into the angle formed by the feather edge and lip of the innersole, means 35 for driving separate staples thru the overworked portions of the upper and transversely thru the lip of the innersole, and means for driving tacks thru other portions of the upper and into the innersole at an 40 angle to the staples.
25. In a lasting machine, the combination with means for working successive portions of an upper over a last having a lipped innersole, means for driving separate fastenings thru the overworked portions of the upper and the lip of the innersole, and means for driving other separate fastenings thru the successively overworked portions of the upper into the body of the innersole 45 where the lip of the innersole is omitted.
26. In a lasting machine, the combination with means for working an upper about a last having a lipped innersole, of means for driving staples thru the overworked portions 55 of the upper and lip of the innersole, and means for driving tacks thru portions of the upper into the body of the innersole about the heel seat to complete the shoe for the inseaming operation.
- 60 27. In a lasting machine, the combination of means for working an upper about a last having a lipped innersole, and means for selectively driving separate fastenings thru the overworked portions of the upper and 65 lip of the innersole and thru other portions of the upper and into the body of the innersole.
28. In a lasting machine, the combination of means for working successive portions of an upper about a last having a lipped innersole, means for driving staples thru the successively overworked portions of the upper and lip of the innersole, means for driving tacks thru other overworked portions of the upper into the body of the innersole, and means und⁷⁰ control of the attendant for selectively driving either staples or tacks.
29. In a lasting machine, the combination of means for working successive portions of an upper about a last having a lipped innersole, and means for selectively driving one character of fastenings thru portions of the upper and lip of the innersole and another character of fastenings thru other portions of the upper into the body of the innersole. 85
30. A machine of the class described, having, in combination, means acting by repeated operations for working successive portions of an upper about a last having an innersole provided with a lip extending along a portion of the innersole, means for driving permanent fastenings thru successively overworked portions of the upper and lip of the innersole, means for driving fastenings thru successively overworked portions of the upper and into the body of the innersole where the lip is omitted, and means for selectively rendering either of 90 said driving means operative at will. 95
31. A machine of the class described, having, in combination, means for working an upper about a last having an innersole provided with a lip, a wiper, means for driving separate fastenings thru overworked portions of the upper and lip of the innersole, means for driving other fastenings thru portions of the upper into the body of the innersole, and means for imparting 100 increased wiping movements to the wiper when the second driving means is operative. 105
32. In a lasting machine, the combination with means for securing an upper in lasted position by independent fastenings which 110 act transversely of the lip, a wiper for forcing the upper into the angle formed by the feather edge and lip of the innersole, and means for varying the wiping movements of the wiper in accordance with the location of 115 the lip from the edge of the innersole. 120
33. In a lasting machine, the combination with means for working an upper over a last having a lipped innersole, of means for securing the overworked upper by independent fastenings which act transversely of the lip, means for securing other portions of the upper by fastenings which act 125 transversely of the body of the innersole, a wiper, and means for automatically 130

changing the wiping movements of the wiper when a change is made in the securing means for the upper.

34. In a lasting machine, the combination of means acting by repeated operations to work successive portions of an upper over a last having an innersole provided with a lip along the sides and around the toe, a wiper, means for driving separate fastenings thru the upper and lip of the innersole along the sides and around the toe, means for driving separate fastenings thru the upper about the heel seat into the body of the innersole, and means for causing the wiper to force the upper into the angle formed by the feather edge and lip and for increasing the wiping movement of the wiper about the heel seat.

35. In a lasting machine, the combination with means for working an upper over a last having a lipped innersole, of means for driving separate fastenings thru the overworked upper transversely of the lip of the innersole, means for driving other fastenings thru the overworked upper into the body of the innersole, a wiper for forcing the upper over the edge of the innersole, and means for automatically varying the wiping movements of the wiper in accordance with the location of the lip from the edge of the innersole and for increasing the movements of the wiper about the unlined portion of the innersole.

36. In a lasting machine, the combination of means for working successive portions of an upper about a last having a lipped innersole, means for selectively driving fastenings thru the overworked upper transversely of the lip of the innersole, and thru the overworked upper into the body of the innersole, a wiper, and means for changing the wiper movements as one or the other driving means is rendered effective.

37. In a lasting machine, the combination of means for working successive portions of an upper about a last having a lipped innersole, a wiper, means for driving staples thru overworked portions of the upper and lip of the innersole, means for driving tacks thru other overworked portions of the upper into the body of the innersole, means under control of the attendant for selectively operating either the staple or tack-driving means, and means for imparting wiper movements to the wiper while driving staples and different wiper movements to the wiper while driving tacks.

38. In a machine of the class described, the combination of means for working an upper over a last having a lipped innersole, means for engaging opposite sides of the lip for clamping it, means for driving fastenings thru the overworked portions of the upper and lip of the innersole while clamped, and means controlled by the posi-

tion of the lip for locating the clamping means.

39. A machine of the class described, comprising, in combination, means for working an upper over a last having a lipped innersole, an edge gage, lip clamping means positioned by engagement with the lip, and means for driving separate fastenings thru overworked portions of the upper and lip of the innersole. 70

40. A machine of the class described, having, in combination, means for working an upper over a last and lipped innersole, an edge gage, lip clamping means including a member to engage the inside of the lip and determine the clamping position of the clamping means by the position of the lip, and means for driving separate fastenings thru the overworked portions of the upper and lip of the innersole. 80

41. In a lasting machine, the combination of means for working an upper over a last and lipped innersole, driving means for driving separate fastenings thru overworked portions of the upper and lip of the innersole, and means for changing the driving position of the driving means in accordance with the changing position of the lip about different parts of the innersole. 90

42. In a lasting machine, the combination of means for working an upper over a last and lipped innersole, an edge gage, clamping means for clamping the lip of the innersole, driving means for driving separate fastenings thru overworked portions of the upper and lip of the innersole, and means for changing the clamping position of the lip clamping means in accordance with the changing position of the lip about different portions of the innersole. 95

43. A machine of the class described, comprising, in combination, means for working an upper over a last and lipped innersole, an edge gage, lip clamping means whose lip clamping position is determined by engagement with the lip, means for driving separate fastenings thru the overworked upper and innersole for permanently securing the upper in lasted position, and means for locking the lip clamp in clamping position. 100

44. In a lasting machine, the combination of means for working successive portions of an upper about a last having a lipped innersole, means for driving staples thru the successively overworked portions of the upper and lip of the innersole, means for driving tacks thru other overworked portions of the upper into the body of the innersole, means under control of the attendant for selectively obtaining either staples or tacks, and means for locking the lip clamping means in lip clamping position. 115

45. In a lasting machine, the combination of means for working an upper over a last and lipped innersole, a lip support adapted 120

to engage the inside of the lip of the innersole and movable to different positions as determined by the position of the lip, means for locking the lip support in operative position, and means for driving separate fastenings thru the overworked portions of the upper and the lip of the innersole.

46. In a lasting machine, the combination of means for working an upper over a last 10 and lipped innersole, a lip support for engaging the inside of the lip, means for driving separate fastenings thru the overworked portions of the upper and lip of the innersole, means for driving fastenings thru other 15 overworked portions of the upper into the body of the innersole, and means for moving the lip support to and from lip supporting position.

47. In a lasting machine, the combination 20 of means for working an upper over a last and lipped innersole, a lip support for engaging the inside of the lip, means for driving separate fastenings thru the overworked portions of the upper and lip of the inner- 25 sole, means for driving fastenings thru other overworked portions of the upper into the body of the innersole, and means for holding the lip support away from lip supporting position while driving fasteners into the 30 body of the innersole.

48. In a lasting machine, the combination of means for working an upper over a last and lipped innersole, means for driving staples thru overworked portions of the upper 35 and lip of the innersole, means for driving tacks thru other portions of the upper into the body of the innersole, a lip supporter, and means for moving the lip supporter into lip supporting position while driving staples and retaining it away from such position while driving tacks.

49. In a lasting machine, the combination of means for working an upper over a last and an innersole having a lip, means for 45 driving separate fastenings thru overworked portions of the upper and lip of the innersole, a lip support for supporting the lip of the innersole while driving fastenings thru the lip, and automatic means for moving the lip support to and from lip supporting position for each fastening driving cycle of the machine.

50. A machine of the class described, having, in combination, means for working an 55 upper over a last having a lipped innersole, means for feeding two characters of fastenings, one for insertion thru overworked portions of the upper and lip of the innersole and the other thru overworked portions of the upper and into the body of the innersole, means for selectively determining which of said fastenings shall be inserted, and means for suspending the feed of one while the other is being inserted.

51. A machine of the class described, hav-

ing, in combination, means for working successive portions of an upper over a last having a lipped innersole, means for driving separate fastenings thru overworked portions of the upper and lip of the innersole 70 and other fastenings thru overworked portions of the upper, counter, and body of the innersole.

52. In a machine of the class described, the combination of shoe positioning means, 75 means for working an upper over a last having a lipped innersole, means for driving separate fastenings thru overworked portions of the upper and lip of the innersole substantially parallel to the plane of the innersole, means for driving other separate fastenings thru other portions of the upper 80 into the body of the innersole substantially at right angles to the direction of the fastenings that pass thru the lip of the innersole, and means for selectively rendering one of said driving means operative and the other functionally inoperative.

53. In a machine of the character de- 90 scribed, the combination of a sole rest and edge gage for positioning a last having a lipped innersole and an assembled upper, means for driving separate fastenings thru the upper and lip of the innersole, and means for driving other separate fastenings thru 95 the upper and into the body of the innersole for securing the upper in lasted position.

54. In a machine of the character de- 100 scribed, the combination of a sole rest and edge gage for positioning a last having a lipped innersole and an assembled upper, a wiper having varying wiper movements for wiping the upper over the edge of the innersole, means for driving separate fastenings thru the upper and lip of the innersole, and 105 means for driving other separate fastenings thru the upper and into the body of the innersole for securing the upper in lasted position.

55. In a machine of the class described, 110 the combination of means for working an upper over a last having a lipped innersole, means for forming and driving staples thru portions of the upper and lip of the innersole, tack driving means for driving tacks 115 thru the upper and into the body of the innersole, and means for interrupting the forming and driving of staples while driving tacks.

56. In a machine of the class described, 120 the combination of means for working an upper over a last having a lipped innersole, means for forming and driving staples thru portions of the upper and lip of the innersole, means for feeding wire to the staple-forming and driving means, tack driving means for driving tacks thru the upper into the body of the innersole, and means for suspending the operation of the wire feeding 125 means while driving tacks.

57. In a machine of the class described, the combination of means for working an upper over a last having a lipped innersole, means for driving separate fastenings thru the upper and lip of the innersole, means for simultaneously driving a plurality of fastenings thru the upper and into the innersole, and means for rendering one of said driving means operative and the other functionally inoperative at will.

58. A machine of the character described, having, in combination, means for driving separate fastenings singly into the work, means for simultaneously driving a plurality of other fastenings into the work, and means for selectively rendering one of said driving means operative and the other functionally inoperative.

59. A machine of the character described, having, in combination, means for driving separate fastenings singly into the work, means for simultaneously driving a plurality of other fastenings into the work at a different angle, and means for selectively rendering one of said driving means operative and the other functionally inoperative.

60. A machine of the character described, having, in combination, means for working an upper over a last having a lipped innersole, means for driving staples thru the upper and lip of the innersole, means for driving a plurality of tacks simultaneously thru other portions of the upper into the body of the innersole, and means for selectively rendering one of said driving means operative and the other functionally inoperative at will.

61. In a machine of the class described, the combination of a slide, means for operating the slide to carry fastenings to inserting position, and means acting at one angle thru the slide for driving fastenings into the work, and means acting at another angle thru the slide for driving other fastenings into the work.

62. In a machine of the class described, the combination of a carrier for carrying fastenings to driving position, means for driving single fastenings of one kind into the work, and means for driving into the work two fastenings of another kind simultaneously, one of the two fastenings being driven at one side and the other at the opposite side of the path of driving of the single fastening and both being closely adjacent to the single fastening.

63. In a machine of the class described, the combination of a carrier for carrying fastenings to driving position, said carrier having a central passageway through which fastenings are driven one at a time when the carrier is in driving position, means for driving said fastenings one at a time, said carrier having one passageway at each side of the central passageway and adjacent

thereto through which two fastenings are driven, and means for driving said two fastenings simultaneously.

64. In a machine of the class described, the combination of means for working an upper over a last having a lipped innersole, means for driving separate fastenings thru overworked portions of the upper and lip of the innersole, and means for driving other fastenings at a different angle thru the upper, the end stiffener, and into the body of the innersole.

65. In a machine of the character described, the combination of means for securing an upper in lasted position, a wiper for wiping the upper over the edge of the innersole, and means for varying the extent of the wiping movements of the wiper.

66. In a machine of the character described, the combination of means for securing an upper in lasted position by the insertion of separate fastenings, a wiper for wiping the upper over the edge of the innersole, and means for varying the extent of the wiping movements of the wiper at different portions of the shoe.

67. In a machine of the class described, the combination of means for inserting fastenings into the work at relatively different angles, a wiper for wiping the upper over the edge of the innersole for the insertion of the fastenings, and means for varying the wiping movements of the wiper.

68. A machine of the class described, having, in combination, a wiper for wiping the upper over the edge of the innersole, means for driving separate fastenings thru the overworked upper and into the material of the innersole to secure the upper in lasted position, and means for varying the extent of the wiping movements of the wiper at different portions of the shoe.

69. A machine of the class described, having, in combination, means for working an upper over a last and edge of an innersole, means for inserting fastenings thru the upper and into the material of the innersole to secure the upper in lasted position, and means for changing the driving position of the driving means to accord with the distance of the lip from the edge of the shoe at different portions of the shoe.

70. A machine of the class described, having in combination, a wiper for wiping an upper over the edge of the innersole, means for varying the wiping movements of the wiper at different parts of the shoe, means for inserting fastenings thru the upper and into the material of the innersole to secure the upper in lasted position, and means for varying the inserting position of the fastening inserting means relative to the edge of the shoe at different portions thereof.

71. A machine of the class described, having, in combination, a wiper for wiping the

upper over the edge of the innersole, means for imparting wiper movements to the wiper to lay the upper into the angle between the feather and lip of the innersole and for varying the wiping movements of the wiper at different parts of the shoe, and means for inserting fastening to secure the upper in overworked position.

72. A machine of the class described, having, in combination, a wiper for wiping the upper over the edge of an innersole, means for imparting a series of wiping movements to the wiper to lay the upper into the angle between the feather and lip of the innersole and increasing the wiping movements of the wiper about those portions of the innersole where the lip is omitted, and means for inserting fastenings for holding the upper in lasted position.

73. In a machine for operating on boots and shoes, the combination of means for locating a shoe in position to be operated upon, means for delivering, separating and driving already formed fastenings into the shoe, and means for forming and driving other fastenings into the shoe.

74. In a machine for operating upon the bottoms of boots and shoes, the combination of means for positioning a shoe to receive fastenings, means for delivering, separating and driving tacks into the shoe bottom, and means for forming and driving staples into the shoe bottom.

75. In a lasting machine, the combination of means for working an upper over a last, means for delivering, separating and driving already formed fastenings into the over-worked upper, and means for forming and driving other fastenings into the over-worked upper.

76. In a lasting machine, the combination of means for working an upper over a last, means for securing the upper by tacks, and means for securing the over-worked upper by staples.

77. In a lasting machine, the combination of means for working an upper over a last, mechanism for delivering, separating and driving already formed fastenings, mechanism for forming and driving other fastenings, and means for rendering either of said mechanisms operative or inoperative each to the exclusion of the other.

78. In a lasting machine, the combination of a reciprocating wiper arranged to move to and fro over a shoe bottom, and means for varying the extent of said wiping movements of the wiper.

79. In a lasting machine, the combination of a reciprocating wiper arranged to move to and fro over a shoe bottom, and means controlled by a characteristic of the shoe bottom for automatically varying the extent of the wiping movements of the wiper.

80. In a lasting machine, the combination

of a reciprocating wiper arranged to move to and fro over a shoe bottom, and means controlled by the location of the sewing lip relatively to the last edge for causing wiping movements of the wiper to correspond to the lip location. 70

81. In a lasting machine, the combination of a reciprocating wiper arranged to move to and fro over a shoe bottom, means controlled by the location of the sewing lip 75 relatively to the last edge for causing wiping movements of the wiper to correspond to the lip location, and means under control of the operator for causing maximum unvarying wiping movements to be imparted 80 to the wiper.

82. In a lasting machine, the combination of a wiper arranged for forward and rearward reciprocation over a shoe bottom, and power means for positively reciprocating 85 the wiper from a constant rearward position to a varying forward position.

83. In a lasting machine, the combination of a wiper arranged for forward and rearward reciprocation over a shoe bottom, a 90 cam for imparting to said wiper minimum forward and rearward movements, and additional means for increasing the movement of the wiper over the shoe bottom.

84. In a lasting machine, the combination 95 of a wiper arranged for forward and rearward reciprocation over a shoe bottom, a cam for imparting to said wiper minimum forward and rearward movements, additional means for increasing the movement 100 of the wiper over the shoe bottom, and means arranged to be set by the operator to cause maximum movements of the wiper to be maintained.

85. In a lasting machine, a wiper for wiping successive portions of an upper into 105 lasted position, mechanism for inserting fastenings of one kind when the upper is being lasted over a lipped innersole and for inserting fastenings of another kind when 110 lasting portions of the shoe where the lip is omitted, means controlled by the innersole lip for determining the extent of movement of the wiper over the feather of the innersole, and means for rendering one 115 fastening inserting mechanism inoperative and the other operative and for causing maximum movement to be imparted to the wiper when lasting the portion of the shoe where the lip is omitted. 120

86. In a lasting machine, the combination of an edge rest for a shoe, a reciprocating wiper arranged to move to and fro over the shoe bottom, and means for varying the distance which the wiper moves over the shoe 125 bottom while the edge rest remains in the same position.

87. In a lasting machine, the combination of a reciprocating wiper arranged to move to and fro over a shoe bottom, and means 130

controlled by a characteristic of the shoe for automatically varying the extent of the wiping movements of the wiper toward the shoe.

- 5 88. In a lasting machine, the combination of an edge rest having a fixed position, a reciprocating wiper arranged to move to and fro over a shoe bottom, and means controlled by the location of the innersole lip or projection relatively to the last edge for causing the wiping movements of the wiper to vary in accordance with the varying distance of the lip or projection from the shoe edge.
- 10 89. In a lasting machine, the combination of a wiper arranged for forward and rearward reciprocation over a shoe bottom, a cam for imparting to said wiper minimum forward and rearward movements, and additional means for increasing the forward movement of the wiper over the shoe bottom while the rearward position remains unchanged.
- 15 90. In a lasting machine, the combination of a wiper arranged for forward and rearward reciprocation over a shoe bottom, a cam for imparting to said wiper minimum forward and rearward movements, additional means comprising a slotted block and a lever for increasing the movement of the wiper over the shoe bottom when the block is positioned with the slot inclined to the direction of movement of the wiper, and means arranged to be set by the operator to hold the block with the slot at its greatest inclination and cause maximum movements of the wiper to be maintained.

- 20 91. In a lasting machine, a wiper for wiping successive portions of the upper into lasted position, mechanism for inserting fastenings of a plurality of different kinds, means controlled by the innersole lip or projection for determining the extent of movement of the wiper over the feather of the innersole when lasting the upper over the lipped portion of the innersole, and means for rendering one fastening inserting mechanism inoperative and the other operative and for causing maximum movement to be imparted to the wiper when lasting the upper over the portion of the innersole where there is no rib or projection.

- 25 92. In a machine for securing an upper to the lip of an innersole in lasted position, the combination of means for locating the shoe in predetermined position, and means acting irrespectively of the location of the lip with respect to the shoe so positioned to clamp the upper and lip together and insert a fastening through the upper and lip.

- 30 93. In a machine for securing an upper to the lip of an innersole in lasted position, the combination of means movable to engage the inner side of the lip, means movable to

press the upper against the outer side of the lip, and mechanism for varying the extent of movement of one of said means in accordance with the lip determined location of the other of said means.

70 94. In a machine of the class described, the combination of means for locating a last, having thereon an upper and a lipped innersole, in predetermined position, relatively movable means for engaging opposite sides of the lip to clamp the upper and lip together, means for causing said means so to clamp the upper and lip irrespectively of the location of the lip with respect to the edge of the shoe so located, and means for inserting fastenings through the clamped upper and lip.

80 95. In a machine for securing an upper to the lip of an innersole in lasted position, the combination of means for locating the shoe in predetermined position, means acting irrespectively of the distance of the lip from the last edge to clamp the upper and lip together, and means for inserting a fastening through the upper and lip substantially parallel to the plane of the innersole.

85 96. In a machine of the class described, the combination of a wiper for working an upper into the angle between the feather and lip of the innersole, an edge gage, a lip supporter, means for relatively operating the wiper and the supporter to clamp the upper and the lip together irrespectively of the distance of the lip from the edge of the innersole, and means for securing the upper and lip together while so held.

90 97. In a machine of the class described, the combination of a wiper for working an upper into the angle between the feather and lip of the innersole, an edge gage, a lip supporter, means for relatively operating the wiper and the supporter to clamp the upper and the lip together irrespectively of the distance of the lip from the edge of the innersole, and means for inserting a staple through the upper and lip and clenching it against the lip supporter.

95 98. In a machine for securing an upper to the lip of an innersole, an edge gage, a lip engaging member whose position is determined by engagement with the lip, means for locating the member in lip engaging position, a nozzle movable in opposition to the member to clamp the upper and lip together, means controlled by said member for varying the movement of the nozzle to cause the upper and lip to be held clamped between the member and nozzle notwithstanding variation in location of the lip at different parts of the innersole, and means for inserting a fastening through the nozzle.

100 99. A machine for securing together an upper and the lip of an innersole having, in combination, shoe positioning means, a lip

supporter, means for moving the supporter yieldingly into engagement with one face of the innersole lip, a stapling nozzle movable in opposition to the supporter toward the 5 opposite face of the lip, mechanism controlled by the position of the supporter to vary the extent of movement of the nozzle to cause the lip and upper to be clamped between the nozzle and the supporter, and 10 means for forcing a staple from the nozzle through the lip and upper and clenching it against the supporter.

100. In a machine for working an upper over a last having thereon a lipped innersole, an edge gage to locate the shoe laterally, clamping means for clamping the upper and lip together, means for changing the 15 position of the clamping means in accordance with the changing position of the lip 20 about different portions of the innersole, and means for inserting separate fastenings through the upper and lip of the innersole.

101. In a machine of the class described, the combination of a measuring element 25 movable to engage the inner face of the lip of an innersole, a wiper movable to press the upper against the outer face of the lip, means for moving said element into contact with the lip, mechanism connected with 30 said element for varying the movement of the wiper in accordance with the position of said element as determined by the lip to cause the upper and lip to be clamped together, and means for inserting a fastening 35 through the clamped upper and lip.

102. In a machine of the class described, the combination of a wiper for working an upper into the angle between the feather and lip of the innersole, an edge gage, a lip 40 supporter, means for automatically operating the wiper and the supporter to clamp the upper and the lip together irrespectively of the distance of the lip from the edge of the innersole, and means for securing the 45 upper and lip together while so held.

103. In a machine of the class described, the combination of a wiper for working an upper into the angle between the feather and lip of the innersole, an edge gage, a lip 50 supporter, means for automatically operating the wiper and the supporter to clamp the upper and the lip together irrespectively of the distance of the lip from the edge of the innersole, and means for inserting a 55 staple through the upper and lip and clenching it against the lip supporter.

104. In a machine for securing an upper to the lip of an innersole, an edge gage, a lip engaging member whose position is determined by engagement with the lip, means 60 for locking the member in lip engaging position, a nozzle movable in opposition to the member to clamp the upper and lip together, means controlled by said member

for varying the movement of the nozzle to cause the upper and lip to be positively held notwithstanding variation in location of the lip at different parts of the innersole, and means for inserting a fastening through the nozzle. 65

105. A machine for securing together an upper and the lip of an innersole having, in combination, a lip supporter, means for moving the supporter yieldingly into engagement with one face of the innersole lip, 70 a wiper, means for giving the wiper a movement of normal extent toward the opposite face of the lip to wipe the upper over the feather and against the lip when the distance of the lip from the shoe edge corresponds to the normal movement of the wiper, mechanism controlled by the position of the supporter as determined by the lip to increase the movement of the wiper when the lip is farther from the shoe edge to cause the lip and upper to be clamped between the wiper and the supporter, and means for inserting a fastening through the 75 clamped portion of the lip and upper. 80

106. In a machine for progressively working successive portions of an upper over a last having thereon a lipped innersole, an edge gage to locate the shoe laterally, clamping means for clamping the upper and lip together, means for changing the position of the clamping means in each cycle of operation in accordance with any change in the position of the lip from the edge of the shoe which may occur at different portions of the innersole, and means for inserting separate fastenings through the upper and lip 100 of the innersole. 105

107. In a machine of the class described, the combination of an edge gage, a measuring element movable to engage the inner face of the lip of an innersole and measure its distance from the edge gage, a wiper movable to press the upper against the outer face of the lip, mechanism connected with the measuring element for varying the movement of the wiper in accordance with the position of said element to cause the upper and lip to be clamped together whatever may be the distance of the lip from the edge gage, and means for inserting a 110 fastening through the clamped upper and lip. 115

108. In a machine of the class described, a wiper for wiping an upper over a last having two passages therethrough for the 120 insertion of fastenings, one of said passages being at approximately right angles to the other.

In testimony whereof we have signed our names to this specification.

MATTHIAS BROCK.
THOMAS H. SEELY.
